DESIGN FOR A PACKING SHEET FOR FRAGILE ARTICLES

Ernest L. Shepard, Fairfield, Maine, assignor, by
mesne assignments, to The Canal National
Bank of Portland, Portland, Maine, a national
banking association

Application May 17, 1945, Serial No. 119,590

Term of patent 14 years

(Cl. D58—16)

To all whom it may concern:

Be it known that I, Ernest L. Shepard, a citizen of the United States, residing at Fairfield, in the county of Somerset, State of Maine, have invented a new, original, and ornamental Design for a Packing Sheet for Fragile Articles, of which the following is a specification, reference being had to the accompanying drawing, forming part thereof.

Fig. 1 is a perspective view of packing sheet for fragile articles showing my new design, this

view particularly illustrating one face of my packing sheet.

Fig. 2 is a view similar to Fig. 1 but particularly illustrating the opposite face of my packing sheet, and

Fig. 3 is an edge view of my packing sheet.

I claim:

The ornamental design for a packing sheet for fragile articles, as shown.

ERNEST L. SHEPARD.
